Attorney

UNITED STATES PATENT OFFICE.

BRYANT H. BLOOD, OF HARTFORD, CONNECTICUT, ASSIGNOR TO PRATT & WHITNEY COMPANY, OF NEW YORK, N. Y., A CORPORATION OF NEW JERSEY.

THREAD-GAUGE CONSTRUCTION.

Application filed August 3, 1921. Serial No. 489,501.

To all whom it may concern:

Be it known that I, BRYANT H. BLOOD, a citizen of the United States, residing at Hartford, in the county of Hartford and State of Connecticut, have invented certain new and useful Improvements in Thread-Gauge Construction, of which the following is a specification.

This invention relates to thread gauges and particularly to means for facilitating the operation and increasing the accuracy of thread gauges.

In performing thread gaging operations, it is essential that the threaded engagement between the gauge and the part being gaged should be free from any obstruction therebetween which might prevent a free gaging contact between such elements. It often happens, however, that dirt, chips or other foreign matter in the threads of the part being gaged prevent such freedom of operation. The primary object of the present invention is to provide a thread gauge with a notch placed at the proper predetermined position therein for receiving any foreign matter in the gaged part before it reaches a position likely to interfere with the gaging operation, such provision in the gauge thereby operating to assure the necessary freedom of contact between the said parts and preventing undue wear of the threaded portions of the gauge.

With the above object in view, my invention consists in the features of construction and operation set forth in the following specification and illustrated in the accompanying drawing. In such drawing annexed hereto and forming a part of this specification, I have shown my invention as embodied in a plug thread gauge but it will be understood that the invention can be otherwise embodied and that the drawing is not to be construed as defining or limiting the scope of the invention, the claims appended to this specification being relied upon for that purpose.

Referring to the figures of the drawing:

Figure 1 is a perspective view of a reversible plug thread gauge embodying the invention.

Fig. 2 is a longitudinal sectional view of the same.

Fig. 3 is an end view thereof.

Fig. 4 is a perspective view of a non-

reversible plug thread gauge embodying the 55 invention.

Referring to Figs. 1, 2 and 3 of the drawing, 1 indicates a reversible gauge provided with gaging threads 2 thereon. The gauge is illustrated as being secured to a 60 gaging handle 3 by means of an axial screw 4, the screw threadedly engaging in the handle and the screw head being adapted to enter a recess 5 in the outer end of the gauge whereby the screw head is flush with 65 the end of the gauge.

As illustrated in Fig. 3, 6 indicates the helical starting portion of the gaging thread which joins the full thread 7 at a point 8. At this juncture of the starting portion of 70 the thread with the full thread, I cut the thread away to provide a notch 9. Such a notch may be provided in both ends of the reversible gauge shown in the drawing. When performing a gaging operation, any 75 dirt, chips or foreign matter in the part being gaged will be forced into this notch before becoming wedged at the full gaging portion 7 of the gaging threads. The gauge, as illustrated, comprises the usual 80 starting thread portion 6, notched portion 9 and a sharp shoulder 10 at the beginning of the full thread 7. It will be noted that this sharp shoulder with the notch just preceding the same, assures a clean thread 85 to be gaged. By placing the notch in the position stated, the benefits derived therefrom are secured without sacrificing any of the advantages of the thread gauge as heretofore constructed, such advantages including 90 the long spiral starting portion 6 of the thread.

In Fig. 4 is illustrated a non-reversible gauge formed in accordance with the invention. This gauge comprises a gaging head 95 11 on a handle 12. The threads 13 of the gauge are provided with a notch 14 at the juncture of the starting portion of the thread with the full thread thereof. The function of the notch and the operation of 100 this gauge is the same as heretofore described.

While in the drawing I have illustrated my invention as applied to plug thread gauges, it will be understood that the same is equally 105 applicable to other forms of thread gauges, such, for example, as ring thread gauges. Various modifications of the invention, as

shown in the drawing, may be made within the scope of the appended claims without departing from the spirit of the invention.

What I claim is:

- 5 1. A thread gauge having a notch formed in one convolution of the gaging thread thereof at the juncture of the starting portion of the thread with the full thread portion thereof, the notch being so formed as
- 10 to provide a sharp shoulder at the begin-

ning of the full thread portion of the gaging thread.

2. A reversible thread gauge having a notch cut in the thread at each end of the gauge, such notch being formed at the juncture of the starting portion of the thread with the full thread portion of the gauge.

In testimony whereof, I hereto affix my signature.

BRYANT H. BLOOD.
